UNITED STATES PATENT OFFICE.

GEORGE C. PINGER, OF BRONXVILLE, AND JAMES F. CURLEY, OF YONKERS, NEW YORK, ASSIGNEES TO CONCRETE STEEL COMPANY, OF NEW YORK, N. Y., A CORPORATION OF DELAWARE.

REINFORCING BAR.

Application filed December 27, 1920. Serial No. 433,116.

To all whom it may concern:

Be it known that we, GEORGE C. PINGER and JAMES F. CURLEY, citizens of the United States, residing, respectively, in Bronxville, county of Westchester, and State of New York, and in Yonkers, in the county of Westchester, in said State, have invented an Improvement in Reenforcing Bars, of which the following is a specification.

10 Our present invention relates to reenforcing metal devices, for use in concrete structures, and has for its object to provide a simple and cheap form of reenforcing bar which can be readily collapsed so that it may 15 be transported, and which can be easily and cheaply made; which will at the same time act as an efficient reinforce and may be employed either for beams or for columns, or under proper conditions for arches and other 20 concrete structures.

The accompanying drawings show an embodiment of our invention. Therein

Figure 1 is a side elevation of a column structure.

25 Figure 2 is an enlarged detail of part of what is shown in Figure 1, also inside elevation.

Figure 3 is a side elevation partly in section, at 90° to Figure 2.

30 Figure 4 is a view similar to Figure 1 of a modified form.

Figures 5 and 6 are details of the modified form.

A is an angle or "spacer," which in the 35 present instance is an L-shaped iron, having webs, as A¹. Slots or cuts A² are made in one of the edges of the angle-iron, and key-hole slots A³ are also made at proper points in the same angle. Disposed in the slots A²

40 is a helical coil B, preferably of drawn wire of large diameter, such as is commonly used in this art. Threaded through the key-hole slots A³ is another wire C which passes first upon one side and then on the other of the

45 web A¹, and is disposed between the edge of the spacing bar and the coils B. In Figure 1 the end of this wire is shown as passed through a round perforation in the web. In

50 general, it need not be fastened securely, as friction holds it in place; but any form of fastening for the end of the wire may be employed.

In Figure 1, the angle-irons, of which there may be one only or more, according 55 to the arrangement desired, are shown as of

light stuff and act as spacers for the coils of the helix B. It will be obvious that if there is one of these, or two disposed upon opposite sides of the helix, the coils may be turned down so that the whole structure will 60 be substantially flat and may be secured in this position and shipped with convenience, additional spacers or angles being placed in position when the bar is put into use, if desired. Also it is not necessary to use angles 65 or T's, as a single strip of flat plate may be employed instead. These variations it is unnecessary to illustrate because they all 70 represent well-known commercial shapes commonly employed in building reinforced 75 concrete structures.

In Figures 4, 5 and 6, we show a modified form which we prefer. In this the parts A, B and C are as before; but the slot A², shown best in Figure 6, which is on a larger 80 scale, has recesses A⁴ upon each side thereof between the main wire B and the edge of the angle in which the retaining wire C is disposed. While this wire is held in place very well by the slots A⁴, additional security may 85 be given to it by distorting the edge of the spacer, as shown best in Figure 5, which is an end elevation of the parts shown in Figure 6. The edge A⁵ is shown as twisted first in one direction and then in the other adjacent to the slots and the wire is woven through these slots, first on one side of the spacer and then upon the other. By this arrangement, there is less liability to displacement of the wire and coil when the concrete is rammed into place. 90

The construction is very rapidly assembled; indeed more rapidly than any with which we are acquainted, as no machine work except cutting the slots is required, and the wire C may be passed by hand through the slots designed for it, and secured at the ends by the blow of a hammer, reducing the 95 labor cost of the whole structure.

We claim as our invention:

1. In a reinforcement for concrete structures, a spacer presenting an outwardly directed flange having slots cut in its edge, a coil disposed in the slots, and a retaining wire extending through the slots entirely in front of the turns of the coil to secure it in 105 place in the slots and extending along the flange alternately first on one side and then on the other side.

2. As a new article of manufacture, a 110

metal reinforcement for concrete comprising a coil, one or more spacers having slots in some of which the turns of the coil are disposed, a wire between the coil and the edge of the spacer for retaining the turns in place, and recesses in the sides of some of the slots in which the wire is retained.

3. As a new article of manufacture, a metal reinforcement for concrete comprising a coil, one or more spacers having slots in their edges in which the turns of the coil are disposed, a wire for holding the turns of the coil in the slots, and recesses in the slots in which the wire is retained; the edges of the spacers being distorted between the

slots to assist in securing the wire in position.

4. As a new article of manufacture, a metal reinforcement for concrete comprising a coil, one or more spacers having slots in their edges in which the turns of the coil are disposed, a wire for holding the turns of the coil in the slots, the spacer having portions distorted out of its plane and engaging the wire to retain it in operative position. 25

In testimony whereof, we have signed our names to this specification this 21st day of December, 1920.

GEORGE C. PINGER,
JAMES F. CURLEY
